UNITED STATES PATENT OFFICE

164,333

CABINET FOR TOILET ARTICLES OR SIMILAR ARTICLE

Anne Schultz, Brooklyn, N. Y.

Application August 9, 1948, Serial No. 148,013

Term of patent 7 years

(Cl. D33—19)

To all whom it may concern:

Be it known that I, Anne Schultz, a citizen of the United States, residing in the Borough of Brooklyn, Kings County, in the city and State of New York, have invented a new, original, and ornamental Design for Cabinet for Toilet Articles or Similar Article, of which the following is a specification, reference being had to the following drawings, forming a part hereof.

Fig. 1 is a perspective view of a cabinet for toilet articles or similar article showing my new design;

Fig. 2 is a front elevational view thereof; and

Fig. 3 is an end elevational view of the same.

What I claim is:

The ornamental design for a cabinet for toilet articles or similar article, substantially as shown.

ANNE SCHULTZ.
